UNITED STATES PATENT OFFICE.

SALATHIEL A. DUKE, OF REINBECK, IOWA.

RAILWAY-TIE.

1,145,296.

Specification of Letters Patent.

Patented July 6, 1915.

Application filed April 21, 1915. Serial No. 22,937.

To all whom it may concern:

Be it known that I, SALATHIEL A. DUKE, a citizen of the United States, residing at Reinbeck, in the county of Grundy and State of Iowa, have invented certain new and useful Improvements in Railway-Ties, of which the following is a specification, reference being had to the accompanying drawings.

10 My present invention relates to new and useful improvements in metallic railway ties and as its primary object aims to provide a tie which is of relatively simple construction and may, therefore, be cheaply manufactured and is so designed that it may be quickly applied to or removed from the road bed.

15 A further and more specific object of the invention is to provide a metallic tie which consists essentially in two rectangular rail base receiving plates which are accompanied by integrally formed rail base engaging jaws and a connecting member.

20 The above, and other incidental objects 25 of a similar nature, which will be herein-after more specifically treated are accomplished by such means as are illustrated in the accompanying drawings, described in the following specification, and then more 30 particularly pointed out in the claims which are appended hereto and form part of this application.

With reference to the drawings, wherein 35 there has been illustrated the preferred embodiment of this invention, as it is reduced to practice, and throughout the several views of which similar reference numerals 40 designate corresponding parts, Figure 1 is a top plan view; Fig. 2 is a longitudinal section; and Fig. 3 is a detail view in top plan of a modified form of connecting member of the rail base receiving plates.

45 Referring now particularly to Fig. 1 of the accompanying drawings, it will be seen that the tie includes as its essential elements, a pair of rail base receiving plates 10 and 11, and a connecting member 12, by means of which the plates are firmly and securely held in the desired spaced relation to each other for supporting the rails in the proper manner.

50 The rail base receiving plates 10 and 11 are similar in construction and formation, each being thickened at its central portion and provided on the upper face thereof with the rail base engaging jaws 13. These mem-

bers 13 are formed as an integral part of the plates, are transversely spaced thereon, and arranged with their adjacent terminals longitudinally spaced. The purpose in thus arranging the jaws is to permit the plate to be disposed diagonally with respect to the rail base, so that this member may be disposed between the jaws and to further permit the turning of the plate to a transverse position with respect to the rail base so that the jaws will engage over the edge portions of the base. Adjacent each terminal of the plate is formed a pair of transversely aligned apertures, as indicated at 14. The apertures at the outer end of each plate are designed to receive relatively long boat spikes 15 which are driven into the road bed and serve to hold the outer ends of the plates against shifting.

55 The connecting member for the rail receiving plates, heretofore designated by the numeral 12 consists in a pair of crossed arms 16 and 17 which are connected by welding at their centers and are arranged to form an X. The terminals of these arms are bent at right angles, producing relatively long spikes 18 which are adapted to be inserted in the apertures at the inner and adjacent ends of the plates. It will be readily observed that the crossed rods serve to rigidly connect the plates, holding them against both turning and longitudinal movement with respect to each other. The spikes 18 are a sufficient length to bite firmly into the 60 road bed for holding the inner ends of the plates against shifting.

65 In the modified form of connecting member shown in Fig. 3, I have provided an X-shaped body member 19, the terminals of the arms of which are provided with threaded sockets which receive the threaded terminals of the rods 20. These rods 20 are provided at their outer ends with spikes similar to the members 18 and form continuations of the arms of the X. Thus in reality, the body member 19 together with the rods 20 constitute a connecting member which is similar to the member 16, except that the rods 20 may be adjusted as to their 70 effective length for spacing the rail receiving plates the distance necessary to properly accommodate them to tracks of different gage.

75 I desire to direct particular attention to 110 the fact that it is not necessary to provide a special form of ballast in the road bed

when the present tie is employed, for the rail receiving plates being relatively wide and long, constitute supporting surfaces of sufficient area to insure the proper support of the rails.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims.

What is claimed is:—

1. A metallic railway tie including a pair of rail base receiving plates disposed in transversely spaced relation to each other with respect to the road bed, and means connecting the adjacent terminals of the plates, said means consisting of a pair of crossed rods having rectangularly bent terminals insertable in the plates and into engagement with the road bed.
2. A metallic railway tie including a pair of rail base receiving plates disposed in transversely spaced relation to each other with respect to the road bed, and a pair of crossed rods rigidly connecting the adjacent

terminals of the plates, said rods being provided with terminal spikes adapted to engage in the road bed for holding the plates against movement thereon.

3. A metallic railway tie including a pair of rail base receiving plates, and a connecting member for maintaining the plates in transversely spaced relation to each other with respect to the road bed, said connecting member including an X-shaped body provided in the terminals of its arms with threaded sockets, and a plurality of rods having their inner ends threaded into the sockets and their outer ends provided with right-angularly extending spikes adapted to pass through the rail receiving plates and into the road bed.

4. A metallic railway tie including a pair of rail base receiving plates, and a connecting member for maintaining the plates in transversely spaced relation to each other with respect to the road bed, said connecting member including an X-shaped body member provided in the terminals of its arms with threaded sockets, and a plurality of rods having their inner ends threaded into the sockets and having their outer ends secured to the plates.

In testimony whereof I hereunto affix my signature in the presence of two witnesses.

SALATHIEL A. DUKE.
